UNITED STATES PATENT OFFICE.

ALVIE E. BICKNELL, OF INDIANAPOLIS, INDIANA.

HOT-WATER HEATER.

1,296,909.

Specification of Letters Patent. Patented Mar. 11, 1919.

Application filed February 14, 1918. Serial No. 217,101.

To all whom it may concern:

Be it known that I, ALVIE E. BICKNELL, a citizen of the United States, residing at Indianapolis, in the county of Marion and 5 State of Indiana, have invented certain new and useful Improvements in Hot-Water Heaters, of which the following is a specification.

My present invention relates to improvements in hot water heaters, of the type involving in its construction upper and lower drums and vertical water tubes with central fuel magazine.

The primary object of the invention is the 15 provision of a hot water heater of the type, adapted for utilizing as fuel either hard or soft coal, and having extensive heating surfaces resulting from the arrangement and combination of parts in such manner that a 20 maximum of heat is generated and radiated to the water surrounding the heated parts, as will be hereinafter more fully described and claimed.

In the accompanying drawings one complete example of the physical embodiment 25 of the invention is illustrated, constructed according to the best mode I have so far devised for the practical application of the principles of the invention.

Figure 1 is a sectional view of a hot water heater involving the invention.

Fig. 2 is a fragmentary, transverse sectional view of the heater or furnace, on line 2—2 of Fig. 1.

Fig. 3 is a fragmentary, sectional view at line 3—3 of Fig. 1, and

Fig. 4 is a fragmentary, sectional view, at line 4—4 of Fig. 1.

In the preferred embodiment of the invention as illustrated in the drawings, a water heater or furnace using coal (either hard or soft) is used, the base ring 1, and all other similar parts, being of either cast iron or pressed steel, and to this open base 40 ring the fire box 2 is bolted, as at 3. The fire box is also of cast iron or pressed steel, somewhat the shape of an inverted, truncated-cone and fashioned with the outwardly flaring flange or ring 4, which ring has attached 45 thereto, as by rivets, the cylindrical jacket 5, preferably of boiler plate, and rising vertically above the firebox-ring. The upper end of this jacket has attached thereto the flanged head 6, rivets 7 being used to secure the jacket and head rigidly and tightly

together. A second water jacket is also used in the construction of the heater, as indicated at 8, this jacket being riveted at 9 to the head ring 6 and extending, centrally, and downwardly into the larger jacket 5. 60

This second water jacket surrounds the inverted, conical shape magazine 10, and the space between these two members, at the bottom, is closed by a small head or ring 11. The magazine and the jacket have their 65 smaller, lower ends located the proper distance above the fire box, and it will be apparent that the outwardly flaring, conical wall of the jacket will be an effective deflector in guiding the flames and gases of 70 combustion upwardly from the fire box, the grate line for supporting the coal in the fire box being indicated at 12 in Fig. 1. At its upper open end, the walls of the conical magazine merge with the upper drum or 75 smoke box 13, the magazine walls also of boiler plate, being riveted at 15 to the top ring 16. This flat ring 16 is supported by the outer, cylindrical casing 17, of boiler plate, an annular gasket or ring 18 being riveted 80 at 20 to the casing, and bolted at 21 to the top ring. At its lower end the casing is riveted at 22 to the base ring, and as the casing surrounds the entire device, with the exception of the upper drum or smoke box, 85 it forms about the fire box, a mud drum 23 for water, a water jacket 24, and the upper water drum 25 surrounding the magazine and above the wall of the outer water jacket. The hot water pipes 26 lead from 90 the upper water drum to the radiators in the various rooms or places to be heated, and the return pipes 27 open into the lower water drum or mud drum 23 about the fire box. 95

One of the special features of the construction of this heater is the utilization of the converging arrangement of water tubes 28 that are fixed, by either welding or expanding, in the flange 4 of the fire box and the small head or ring 11 of the magazine. 100 These tubes are spaced apart and extend across the intervening space between the larger upper end of the fire box, and the comparatively small end or throat of the magazine containing the fuel, so that the fumes, gases of combustion, or flames, emerging from, or emitted by the fuel as it burns, pass directly between these tubes and around them and they are thus arranged to expose their contained water to the action of 105 119

the heat. A second annularly arranged series of water tubes 29, surround the first or inner series, and part of the magazine, and the whole of the magazine water jacket. 5 These tubes are also inclined toward each other, or are located on converging lines, and the tubes are welded or expanded in the flange 4 and the head or large ring 6. These two series of water tubes provide for 10 a continual and effective circulation, the shorter tubes connecting the lower mud drum with the magazine water jacket, and the longer tubes connecting the mud drum with the upper water drum 25. It will be 15 apparent that the flames pass through both the short and longer series of water tubes, and from thence the flames, gases, and fumes pass upwardly from the combustion chamber 8', in which are located the water tubes, thence through the fire or smoke flues 30 into the smoke box 13, and from 20 there are carried off through the smoke pipes 31 to the chimney.

The arrangement and construction of the 25 furnace or heater above described, gives free access to the several parts, particularly the interior parts which contain the water tubes and smoke flues, so that repairs may readily be made without the necessity for 30 disconnecting the heating system from the main portions of the boiler. It will be obvious that practically all parts of the boiler are effective in radiating heat so that the water may be heated quickly and effectively, and the rapid and free circulation of 35 water throughout the several parts of the boiler, as described, provide a thoroughly practical heating system giving maximum heat with a minimum of fuel.

40 The heater does not contemplate the use of fuel doors, but is of the magazine feed type for the fuel, the kindling being fed into the fire box through the magazine, and

then the magazine is filled as usual to supply the fuel.

45

What I claim is:—

1. In a water heater the combination with a casing and a firebox forming a mud drum therein, return water pipe connections, an upper annular outwardly projecting flange 50 to the firebox and a cylindrical drum secured thereon providing a water jacket in conjunction with the casing, a central inverted conical magazine above the firebox, a head ring closing the upper end of the cylindrical drum and an inverted conical jacket 55 wall secured to said head, surrounding the magazine and forming a water jacket thereabout, a series of water tubes connecting the mud drum and magazine water jacket, 60 a smoke box surrounding the upper end of the fuel magazine, and smoke flues connecting said smoke box and the interior of the cylindrical drum, and said drum being in open communication with the fire box.

65

2. The combination in a water heater with a casing, of an open, central firebox and an enlarged drum superposed thereon to form a mud drum beneath the enlarged drum and a water jacket in conjunction with the 70 casing, an open bottom, central magazine forming a smoke box in the upper end of the casing, and projecting into the enlarged drum, there being a water drum formed between said smoke drum and the enlarged 75 drum, a water jacket within the enlarged drum surrounding the magazine, water pipes connecting the mud drum and magazine water jacket and arranged in an annular series to bridge the space between the 80 firebox and the bottom of the magazine, smoke flues connecting the enlarged drum and smoke box, and return water pipe connections.

75

In testimony whereof I affix my signature. 85
ALVIE E. BICKNELL.
